PEN

Carey Garfield Gregory, Los Angeles, Calif.

Application July 20, 1936, Serial No. 91,585

4 Claims. (Cl. 120—113)

My invention relates broadly to writing pens and more particularly to an improved construction of writing pen which is adapted to automatically fill with ink by a simple dipping operation and feed the ink to the writing pen with relatively infrequent refilling operations.

One of the objects of my invention is to provide a construction of writing pen having storage means for ink adapted to be filled automatically by a simple dipping operation and operating to continuously feed ink to the pen, necessitating only infrequent dipping of the pen in the supply source for replenishing the ink in the storage means.

Another object of my invention is to provide an automatically filling pen structure having a tubular barrel forming a hand grip in which the expansion of air may be controlled in taking up a quantity of ink for subsequent feed to the writing pen in accordance with writing requirements.

A further object of my invention is to provide a construction of storage feed pen in which the thermal effects of the hand in gripping the pen barrel are compensated by release of pressure caused by expansion of air in the pen barrel when held in the hand for avoiding flooding out of ink in the storage feed during writing operations.

A still further object of my invention is to provide a construction of storage feed pen having special means for avoiding surplusage of ink either on the pen point or adjacent the pen holder and increasing the convenience and efficiency in the use of the writing pen.

Still another object of my invention is to provide a construction of storage feed pen adapted to be dipped from time to time through a pre-formed guide carrier in an inkwell, having means coacting with the guide carrier for draining off any accumulated ink and preventing drip of ink from the pen.

Other and further objects of my invention reside in the construction of storage feed pen having automatic air expansion control means as set forth more fully in the specification herein-after following by reference to the accompanying drawing in which:

Figure 1 is a side elevation of my improved pen showing it inserted in the guide receptacle of an inkwell; Fig. 2 is a fragmentary, top plan view of the forward end of the pen, parts of the pen being broken away in order to show the arrangement of the storage feed for the pen; Fig. 3 is a central vertical longitudinal section of the forward end of the pen, the feed being shown in side elevation; Fig. 4 is a similar view with the

feed being shown in section to disclose more specifically, the storage recess within the forward end of the feed; Fig. 5 is a transverse vertical sectional view taken on line 5—5 of Fig. 4; Fig. 6 is a perspective view of one form of cylindrical plug used in association with my improved pen; Fig. 7 is a fragmentary side elevation showing a modified form of cylindrical plug for the pen of my invention; Fig. 8 is a perspective view thereof; and Fig. 9 is a front elevation thereof showing more particularly the general formation of the headed end of the cylindrical plug.

My invention is directed to an improved construction of pen in which a storage feed is provided for retaining an adequate amount of ink by dipping of the pen into an ink well to insure a continuous writing operation and to insure a supply of ink for a substantial period of time for continuous writing operation and making it unnecessary to repeatedly dip the pen into the ink-well at frequent intervals. The pen is provided with a feed having a relatively deep capillary channel or groove formed therein and connected through a tapering passage to the hollow interior section of the tubular barrel of the pen holder. The storage feed receives a sufficient quantity of ink upon each dip operation of the pen to insure a continuous supply of the ink to the pen for a substantial period of time. The amount of ink the storage feed collects is regulated and limited by the capillary action of the channel connected with the storage feed. When the storage feed absorbs ink to the full capacity, any expansion of air in the tubular barrel of the pen holder which is directly connected at the back of the feed, would normally act upon the ink in the storage feed and cause the flooding out of ink from the storage feed. I avoid such detrimental flooding action by providing a small pressure release aperture in the pen barrel. As the air expands in the pen barrel, when the pen is held in the hand, the air is allowed to escape through the pressure release and does not act detrimentally to cause flooding out of the ink. Thus, considerable latitude is provided for allowing the storage feed to collect ink and deliver the required quantity of ink for efficient writing purposes. By providing a path interconnecting the storage feed reservoir with the pressure release in the tubular barrel of the pen, a uniform amount of ink is collected by the pen for uniform distribution during writing operation of the pen.

I provide an annular channel around the section of the plug between the headed end and

the forward end of the plug. This channel is so designed that the end section will not operate as a capillary or pick up the drip of previous ink which may be collected on the side wall of 5 the funnel forming the pen guide receptacle. In order to further prevent the collection of surplus ink on the end section of the plug, a longitudinally extending channel or channels may be cut through the collar on the headed 10 end of the pen for lessening the amount of ink picked up by the end section when it is rapidly withdrawn from the funnel of the guide receptacle of the ink well. The several features of 15 the pen of my invention including the storage reservoir, the pressure conducting channel, the pressure release, the headed end of the cylindrical plug, the longitudinal channels in the annular collar of the headed end of the cylindrical plug; all coact to insure the efficient operation of the 20 pen.

Referring to the drawing in more detail, reference character 1 designates the pen barrel having a hollow tubular end section 2, a central hollow tubular finger grip section 3 and a solid 25 end section 4. The solid end section 4 connects with the central tubular finger grip section 3 by means of the plug extension 5 which fits into the tubular end of the central finger grip section 3. The hollow tubular end section 2 is 30 provided with an annular cylindrical shoulder 6 on the end thereof from which the exterior surface of the hollow tubular end section tapers to a smaller cross-section in a zone indicated generally at 7 from which the diameter of the 35 pen holder gradually increases to the diameter of the central finger grip section indicated at 3. The hollow construction of the pen holder is shown more clearly in Fig. 3, from which it will be seen that the adjoining sections 2 and 3 have 40 a hollow interior shown at 8. A cylindrical plug 9 shown more particularly in Fig. 6 provided with an annular connecting portion 10 frictionally engages the internal bore 8 in the end section 2 of the pen holder, providing a relatively 45 tight interengaging fit therewith. The cylindrical plug 9 has an annular headed end 11 as shown more particularly in Fig. 6. The headed end 11 is formed by the junction of two angularly disposed face portions 12 and 13. The 50 angular disposition of face 12 is less than the angular disposition of face 13, for facilitating the entry of the pen into a funnel shaped guide receptacle for pens such as the funnel guide receptacle shown at 14, in Fig. 1.

The funnel shaped guide receptacle 14 in Fig. 55 1 is disposed in an angular position through an aperture 15 in the top wall of an ink well which may be molded from ceramic material as illustrated at 16. It will be seen that the peripheral edge of the circular end shoulder 6 abuts against the outwardly flared wall of the funnel shaped pen guide receptacle 14, while the headed end 11 centers the pen within the pen guide receptacle in a position in which the pen point 17 dips into the pool of ink shown at 18 in the ink well 16. It will be observed that an annular cylindrical zone 19 is provided between the headed end 11 and the annular connecting portion 10. This insures against the capillary movement 60 of ink from the pen point in a path up the pen holder, which might be detrimental in that the writer might get ink on the fingers.

In order to avoid the tendency of capillary action of the ink along the plug toward the 65 pen holder, I may provide longitudinally extend-

ing channels, grooves, or recesses in the headed end 11, as I have illustrated more clearly in Figs. 7, 8 and 9 where the annular headed end is broken into segments, as indicated at 28. The 70 grooves, recesses, or channels 29 between segments 28 allow ink which may tend to move by capillary action toward the pen holder, to drip back into the ink receptacle. 5

The cylindrical plug 9 has an internal bore 20 into which the pen point 17 is secured by 10 means of feed plug 21. Feed plug 21 is provided with a multiplicity of laterally extending grooves 22 which serve to collect and retain ink to be fed to the pen point 17 by capillary action. The group of laterally extending grooves 15 22 are spaced from the central portion of the plug 21 by gaps 22a. I do not rely, however, upon this method of capillary feed. In addition I provide a relatively deep curved recess 23 in the feed plug 21, immediately below the nib of 20 the pen. The curved recess 23 is relatively deep and operates as a storage chamber for feeding ink to the pen nib. The storage feed chamber 23 connects to the interior bore 8 of the pen holder 1 through a tapered groove 24 in the 25 plug 21. The tapered groove 24 is provided with a multiplicity of longitudinally extending feed grooves 25 by which additional ink may be taken up by capillary attraction beyond the limits of the capacity of the storage feed reservoir. 30 The groove 24 provides a path for air into the interior of bore 8. The heat of the hand as it grasps the pen barrel at the central section 3 and the end section 2 would normally tend, by 35 expansive action to flood the ink out of the channel 24 and displace some of the ink from storage feed reservoir 23, causing blots. However, I provide in the hollow tubular central section 3, a pressure release aperture 26 by which air, as it expands under the thermal influence 40 of the hand is allowed to escape.

I have found the pen construction of my invention highly practical in manufacture, production and operation. A sufficient quantity of 45 ink is retained in the storage feed reservoir 23 and groove 24 to allow uniform feeding of ink to the pen nib for substantial periods of time, thus making it unnecessary to make frequent dips of the pen into the ink well.

While I have described my invention in certain 50 of its preferred embodiments, I desire that it be understood that modifications may be made and that no limitations upon my invention are intended other than may be imposed by the scope of the appended claims.

What I claim as new and desire to secure by Letters Patent of the United States is as follows:

1. A dip pen including a pen holder having a hollow barrel portion, a tubular plug secured in the end of said hollow barrel portion, a storage 60 feed plug insertable into the bore of said tubular plug for securing a pen point intermediate said feed plug and the inner wall of said tubular plug with respect to said pen holder, and an annular head on said tubular plug, said annular head having a plurality of longitudinally extending grooves therein for dividing said annular head into segmental portions for obstructing the capillary movement of ink in a direction from the pen point towards the pen holder and allowing discharge of ink collected by the segmental portions of said annular head in dipping operations. 65

2. A fountain-feed dip pen including a pen holder having a hollow barrel portion, a tubular plug having a cylindrical wall engaging 70

portion on one end for frictionally engaging the inner wall of the hollow barrel portion of said pen holder, a headed end on said tubular plug constituted by a pair of inclined faces, the face adjacent the extreme end of the tubular plug being inclined at a smaller angle with respect to the axis of the tubular plug than the face more remote from the extreme end of the tubular plug, an annular cylindrical zone between said cylindrical wall engaging portion of said tubular plug and said headed end, a feed plug, and means for securing a pen point in writing position intermediate the end of said tubular plug and the exterior surface of said feed plug, the headed end of said tubular plug having a channel therein extending from the end of the tubular plug to the annular cylindrical zone intermediate said headed end and said cylindrical wall portion for releasing ink collected in said annular cylindrical zone.

3. A dip pen holder comprising a tubular body portion, closure means at one end thereof, pen point engaging means at the other end thereof, said pen point engaging means having an ink storage reservoir communicating with the interior of said tubular body portion, said tubular body portion having means for venting the interior

thereof for controlling the rate of capillary filling of the pen when dipped in ink and an annular head on said closure means, said annular head having a plurality of longitudinally extending grooves therein for dividing said annular head into segmental portions for obstructing the capillary movement of ink in a direction from the pen point towards the pen holder and allowing discharge of ink collected by the segmental portions of said annular head in dipping operations.

4. A dip pen comprising a holder, a pen point secured with respect to said holder, an annular head on the end of said holder intermediate said pen point and said holder, a substantially cylindrical portion on said holder intermediate said annular head and said holder, said annular head having a plurality of longitudinally extending grooves therein for dividing said annular head into segmental portions for obstructing the capillary movement of ink in a direction from the pen point towards the pen holder and allowing discharge of ink collected by the segmental portions of said annular head and from the substantially cylindrical portion of said holder in dipping operations.

CAREY GARFIELD GREGORY.
